(57) CLAIM

I claim an ornamental design for a golf ball cleaner, as shown and described.

DESCRIPTION

FIG. 1 is an exploded front perspective view of a golf ball cleaner;

FIG. 2 is an exploded rear perspective view thereof;

FIG. 3 is an exploded top perspective view thereof;

FIG. 4 is an enlarged bottom front perspective view of the cover portion;

FIG. 5 is a bottom rear perspective view of the base portion;

FIG. 6 is an enlarged rear perspective view of the base portion;

FIG. 7 is a front elevational view of FIG. 4;

FIG. 8 is a rear elevational view of FIG. 4;

FIG. 9 is a top plan view of FIG. 4;

FIG. 10 is a bottom plan view of FIG. 4;

FIG. 11 is a side view of FIG. 4;

FIG. 12 is an opposite view of FIG. 11;

FIG. 13 is a front elevational view of FIG. 6;

FIG. 14 is a rear elevational view of FIG. 6;

FIG. 15 is a top plan view of FIG. 6;

FIG. 16 is a bottom plan view of FIG. 6;

FIG. 17 is a side view of FIG. 6; and,

FIG. 18 is an opposite view of FIG. 17.
